CIRCUIT BREAKER

John W. May, Pittsburgh, William H. Stuellein, East McKeesport, and Merl E. Horn, Forest Hills, Pa., assignors to Westinghouse Electric Corporation, East Pittsburgh, Pa., a corporation of Pennsylvania

Application December 17, 1941, Serial No. 423,360

8 Claims. (Cl. 200—89)

This invention relates to circuit breakers, and more particularly to trip-free circuit breakers wherein the contacts are trip free of the closing means.

Under certain circumstances, it is desirable to positively hold a circuit breaker in closed circuit condition against any force acting to cause opening of the breaker whether such force is due to an overload on the circuit controlled by the breaker, or due to shocks or jars.

It is an object of this invention to provide an improved circuit breaker in which the movable contacts are trip free of the closing mechanism and which is provided with manually operated means to prevent opening of the contacts.

Another object of the invention is to provide a circuit breaker with means operable to prevent opening of the breaker either in response to abnormal conditions or by jars or shocks.

Another object of the invention is to provide an improved circuit breaker with novel means for positively locking the operating mechanism against circuit opening movement.

Another object of the invention is to provide a trip-free circuit breaker having manually operable means for preventing opening movement of the contacts.

Another object of the invention is to provide a circuit breaker with an improved locking device which is operable to render the tripping means ineffective to trip the breaker and which prevents operation of the operating mechanism to open the contacts.

Another object of the invention is to provide an improved circuit breaker wherein a toggle is operated to effect tripping of the breaker with a manually operable interposer to prevent tripping operation of the toggle.

Another object of the invention is to provide an improved circuit breaker in which the operating mechanism comprises a linkage including a plurality of toggles with manually operable means for preventing opening operations of the linkage.

Another object of the invention is to provide an improved circuit breaker in which a linkage is collapsible to cause opening of the contacts of the breaker with a single manipulative means engageable with different parts of said linkage to lock the breaker in closed circuit position.

The novel features that are considered characteristic of the invention are set forth in particular in the appended claims. The invention itself, however, both as to structure and operation, together with additional objects and advan-

tages thereof will be best understood from the following detailed description of several embodiments thereof when read in connection with the accompanying drawings, in which:

5 Figure 1 is a vertical sectional view through the center pole of a three-pole circuit breaker embodying the features of the invention.

Fig. 2 is a fragmentary plan view of a part of the circuit breaker showing the manual locking device.

Fig. 3 is a side elevational view of the circuit breaker illustrating a modified form of the locking device.

Fig. 4 is a fragmentary detail view showing the operating knob and the indicating device of the modified form of the invention, and

Fig. 5 is a fragmentary sectional view taken on line V—V of Fig. 3 and showing the pull rod locking device.

Referring to Fig. 1 of the drawings, the circuit breaker is provided with a common operating mechanism which is mounted in a U-shaped main frame 16 having parallel sides 17 joined by a cross member 19. The frame 16 is secured to the center portion of an insulating base 11 by means of bolts 21 and 23, and the outer ends of the sides of the frame are rigidly connected by a cross member 25.

The bolt 23 extends through the cross member 19 and serves to rigidly secure a connector 27 of conducting material to the cross member and to the base 11. A shaft 29 extends through an opening in the connector 27 and through openings in the sides of the frame 16 and pivotally supports a

35 pair of arms 31 having their outer ends integral with a contact arm 30 for the center pole. The contact arms for the outer poles are not shown in the drawings but each comprises a structure similar to the contact arm 30 for the center pole

40 without the arms 31. The contact arms for the outer poles are rigidly secured to a tie bar 67 which extends across all three poles and which is clamped to the contact arm 30 for the center pole by a clamp 78 and a screw 71, each of the contact arms being insulated from the tie bar 67 by means of sheaths of insulating material 69 between the tie bar 67 and the contact arms 30 for the several poles.

The contact structure for the several poles of the breaker are alike for which reason only the structure for the center pole will be described. The contact arm 30 pivotally carries a main contact member 47 and an arcing contact member 55. The main contact member 47 is pivoted on a pivot 49 in projections 51 of the arm 30, and the arcing

contact member 55 is pivoted on a pivot pin 57 in projection 59 of the arm 30.

The contact member 47 carries a contact 33, and a contact 35 is secured to the arcing contact member 55. These contacts 33 and 35 are adapted to engage respectively fixed contacts 39 and 37 secured on a conductor 41. The conductor 41 which is secured to the base 11 by bolts 43 extends upwardly and a bent portion thereof extends through an opening in the base 11, forming a terminal connector 45.

A spring 53 compressed between spring seats on the contact arm 30 and on the contact member 47 provides contact pressure for the main contacts 33-39. Contact pressure for the arcing contacts 35-37 is provided by a spring 63 surrounding a rod 61 pivotally connected to the contact member 55. The spring 63 is compressed between a collar 65 seated on a shoulder on the rod 61 and the bottom of a recess formed in the contact arm 30. The rod 61 slidably projects through an opening in the recessed portion of the arm 30 and has a nut 75 on the end thereof, the nut 75 acting to limit counterclockwise rotation of the contact member 55 about its pivot 57 when the arm 30 is moved to open the contacts. Counterclockwise movement of the main contact member 47 is limited by a shoulder 73 therein striking the body of the arm 30. The adjustment of the nut 75 on the rod 61 is such that the main contacts 33-39 open before the arcing contacts 35-37 open.

When the arm 30 is operated to open the contacts the arc resulting from the rupture of the current is extinguished by an arc extinguisher indicated generally at 76, there being one arc extinguisher for each pole of the breaker. While any suitable extinguisher may be employed, the one illustrated is of the spaced plate type and comprises, generally, a stack of slotted plates (not shown) disposed adjacent the path of travel of the arcing contact 35. The plates serve to draw the arc toward the ends of the slots where it is broken up into a plurality of short arcs which are quickly cooled and extinguished.

The arcing contact member 55 is connected by a flexible shunt conductor 11 to the main contact member 47 and this member is connected by means of a flexible shunt conductor 79 to the connector 27. Secured to the connector 27 by means of bolts 74 is a downwardly extending conductor 81 which is bent at right angles and extends between the legs of a U-shaped tripping magnet core 161 and through an opening in the base 11. The end 83 of the conductor 81 forms a terminal connector which, together with the terminal connector 45 serves to connect the breaker in an electrical circuit.

The electrical circuits for the several poles of the breaker are essentially the same; therefore, only the circuit for the center pole will be described. This circuit extends from the terminal connector 45 through the conductor 41, the main contacts 33-39, the main contact member 47, the flexible shunt conductor 79, the connector 27, the conductor 81 to the terminal connector 83. The circuit for the arcing contacts extends from the conductor 41 through the arcing contacts 37-35, the arcing contact member 55, the flexible shunt conductor 11, the main contact member 47 and over the previously described circuit to the terminal connector 83.

The contact arm 30 for the center pole is biased in a clockwise (Fig. 1) or opening direction by a pair of springs 85. These springs are tensioned between a fixed pivot 87, on the frame 16, and 75

the contact arm 30. However, under normal circuit conditions, the contact arm 30 is releasably restrained in its closed contact position by means of a toggle and linkage which is collapsible to effect opening of the contacts.

This collapsible linkage includes a lever 89 pivotally mounted on a fixed pivot 91 supported on the main frame 16, the lever 89 comprising a pair of levers rigidly connected by a cross member 117. The lever 89 is operatively connected to the arms 31 of the center pole contact arm 30 by a main operating toggle comprising a toggle link 93 having one end pivoted on a pin 101 on the lever 89 and a toggle link 95 having one end pivoted on a pin 99 supported on the arms 31. The link 95 comprises a pair of links rigidly joined by a cross bar 115 and is pivotally connected to the link 93 by means of a knee pin 97.

The free end of the lever 89 is connected by a link 103 to one arm of a lever 105 pivoted on the fixed pivot 87. The other arm of the lever 105 is pivotally connected to a toggle link 107 of a tripping toggle comprising the link 107 and a toggle link 109 pivoted on a fixed pivot 113 in the frame 16, the toggle links 107 and 109 being pivotally connected by a knee pin 111.

The toggle link 107 comprises a pair of links connected by a yoke 119 having a bent portion to which is secured an extension 121, the purpose of which is to cooperate with a manual handle 141 to trip the breaker, as will be more fully brought out later. The toggle link 109 comprises a pair of links joined by a yoke 123 having formed portions 125 and 127 thereon. The lever 105 comprises a pair of levers rigidly connected by a yoke 106, and the link 103 comprises a pair of links joined by a yoke 104.

The linkage just described, under normal conditions serves to releasably hold the contact assembly including the movable contacts for all of the poles in closed contact position. In this position the main operating toggle 93-95 is over center above a line through the center of the pins 99 and 101. A second toggle, one link of which comprises the overcenter links 93 and 95, and the other link of which comprises the lever 89, is over center above a line through the centers of the pins 99 and 91. The overcenter movement of the main operating toggle 93-95 is limited by the projecting end of the link 93 engaging the cross bar 115 of the toggle link 95.

With the main operating toggle 93-95 and the toggle comprising links 93-95 and lever 89 in their overcenter position, as shown in the drawings, the springs 85 and the three sets of contact pressure springs 53 and 63 bias the lever 89 in a clockwise direction. Movement of the lever 89, however, is normally prevented by the tripping toggle 107-109 which is biased over center to the left of a line drawn through the center of the fixed pivot 113 and the point of connection of the toggle link 107 with the lever 105, by means of a spring 128 tensioned between the yoke 119 and the fixed pivot 113. The overcenter position of the tripping toggle 107-109 is adjustably determined by the formed portion 125 of the yoke 123 engaging an adjusting screw 129 in the cross member 25 of the frame 16. The tripping toggle 107-109 in its overcenter position, acting through the lever 105 and link 103, prevents clockwise rotation of the lever 89, and consequently holds the contact assembly in the closed contact position against the biasing influence of the springs 85 and the springs 53 and 63.

The tripping toggle 107-109 is adapted to be

moved over center outwardly in a direction toward collapsed position to cause opening of the contacts by means of a trip device indicated generally at 133. The trip device, when operated in response to an overload current, actuates a trip rod 135 which is slideable vertically through a shunt trip coil (not shown) enclosed in a casing 138 secured to the main frame 16. The shunt coil is adapted to be energized from a suitable source either automatically, or by a manual control switch, in a manner well known in the art to operate the trip rod 135 from a remote point.

When operated either by the shunt coil or by the trip device 133, the trip rod 135 is thrust upwardly and strikes the formed portion 121 of the yoke 123 of the link 109 and rocks said toggle link clockwise about the fixed pivot 113. This movement causes collapse of the tripping toggle 107-109 permitting the springs 85 to rock the contact assemblage clockwise to open the circuit.

The main operating toggle 93-95 does not immediately collapse, but the force of the springs 85 applied through the main operating toggle causes collapse of the toggle comprising links 93-95 and the lever 89 rocking the lever 89 clockwise as viewed in Fig. 1. This movement is transmitted through the link 103 and lever 105 to complete the collapse of the tripping toggle 107-109.

The clockwise or opening movement of the contact arm 30 is arrested by projections (not shown) thereon striking a portion 137 of the frame 16. At this time the rebound of the inertia of the main operating toggle 93-95 starts said toggle over center in a direction to cause its collapse. By the time the knee pin 91 of the main toggle passes over center below the line 99-101 the weight of the parts causes the main toggle 93-95 to collapse and causes the lever 89, link 103, lever 105 and the tripping toggle 107-109 to be automatically reset to their normal positions. The main operating toggle 93-95 remains in its collapsed position until the breaker is closed.

The contacts are closed manually by operation of the previously mentioned handle 141. The handle is secured to the outer end of a short shaft 142 rotatably mounted in a bracket 143 of insulating material which is secured to the outer end of the frame 16. A crank arm 144 secured on the shaft 142 has a depending link 151 pivotally connected to its free end. The lower end of the link 151 is notched and engages an hour glass-shaped roller 153 rotatably mounted on a cross member 147 rigidly connecting the outer ends of a pair of levers forming a contact closing lever 145. The levers 145 are disposed one adjacent to each side of the frame 16 and are pivotally supported on the fixed pivot 91 the ends of which project beyond the sides of the frame 16 (see Fig. 2). The inner ends of the levers 145 are rigidly connected by a cross bar 149 from which extend spaced projections 152. A roller 155 is rotatably mounted on a pin 157 supported in the projections 152.

The contacts are closed manually by clockwise rotation of the handle 141 which thrusts the link 151 downwardly and rotates the contact closing lever 145 in a clockwise direction. During this movement of the lever 145 the roller 155 engages the link 93 of the now collapsed operating toggle 93-95 and moves this toggle to its extended over-center position. Since at this time the tripping toggle 107-109 is over center in its restraining position, rotation of the lever 89 is prevented, and consequently the force applied to straighten

the toggle 93-95 rotates the contact arm 30 counterclockwise to close the contacts and to tension the springs 85. The clockwise movement of the closing levers 145 moves the toggle 93-95 over center above the line 99-101 so that the contacts are held in the closed position until the breaker is again tripped.

A spring 159 having one end anchored to the lever 145 and the other end secured to the frame 16 is provided to restore the lever 145 and the handle 141 to their normal positions upon release of the handle following a contact closing operation.

The contact closing lever 145 may be operated to close the contacts automatically by means of an electric motor 139. The motor is securely mounted on a plate 140 suitably attached to one side of the main frame 16, and may be energized from any suitable source. When energized the motor is adapted to rotate a crank disc 130 which carries an anti-friction roller 131. During this rotation the roller 131 engages a cam face 132 of an arm 134 secured to the side of the closing lever 145 and rotates said arm and the lever 145 clockwise to effect closing of the contacts in the manner previously set forth. As soon as the roller 131 passes out of engagement with the arm 134 the spring 159 acts to restore the closing lever 145 to its normal position. The motor 139 is deenergized by a suitable limit switch (not shown).

The circuit breaker may be tripped manually by rotating the handle 141 through a small angle in a counter-clockwise direction from its neutral position. When the handle is rotated counterclockwise it raises the link 151. During this movement a projection 150 on the link engages the previously described extension 121 on the yoke 119 of the toggle link 107, and rocks the link counterclockwise about its point of connection with the lever 105. This moves the tripping toggle 107-109 over center in the direction to cause its collapse and effect opening of the contacts in the manner previously described.

It was stated previously that the trip rod 35 is operated to effect tripping of the breaker by means of a trip device 133. There is a trip device 133 provided for at least two of the poles of the breaker but since they are alike only the trip device for the center pole will be described. This trip device includes the magnet core 161 and a frame comprising substantially parallel side members 163 rigidly connected by a yoke 165. The members 163 are provided with mounting feet 167 and bolts 169 extend through openings in the base 11, the magnet core 161 and the feet 167 to rigidly secure the members to the base. A trip lever 173 is pivotally mounted on a rod 175 extending between and supported in the frames 163. The trip lever comprises a pair of spaced levers 173 having an armature 179 secured to one end, and connected by a yoke 177 at the other end. The trip lever is biased against operation by the magnet by a spring 191 having one end hooked onto the yoke 177 and the other end hooked onto a vertically movable plate 193. An adjusting screw 195, provided with a knurled head 197 bearing against a formed projection 199 of the yoke 165, passes through an opening 201 in the plate 193 and is provided with screw threads for moving the plate vertically to adjust the tension of the spring 191. Spaced projection 203 on the yoke 165 serves to support a scale plate 203 which bears suitable indicia indicating the adjustment of the spring 191 as the tripping point

of the breaker. An adjustable stop screw 205 in the yoke 166 is provided with a lock nut 207 and determines the open air gap of the magnet.

Rotatably mounted in a bracket 189, secured to the casing 138 housing the shunt trip coil, is a trip bar 187 extending across all of the poles of the breaker. A plurality of arms 185, one for each trip device is secured to the trip bar 187, the center one of the arms being disposed in alignment with the trip rod 135. An adjustable screw 181 is mounted in each of the yokes 177 in alignment with the arm 185 for its pole.

Normal rated current flowing through the circuit of the breaker causes slight energization of the magnet 161. This energy, however, is insufficient to overcome the tension of the spring 191. Upon the occurrence of an overload current above a predetermined value the flow of current through the conductor 81 energizes the magnet sufficiently to cause it to attract the armature 179 and operate the trip lever 173. Operation of the trip lever causes the screw 181 to rock the arm 185 and the trip bar 187 clockwise which, as previously described, thrusts the trip rod 135 upwardly to effect tripping of the breaker.

It was stated previously that under certain circumstances it is desired to hold the contacts of the breaker inclosed position against any force acting to cause opening of the contacts. This is effected by manually locking the toggle and linkage mechanism in a manner to prevent collapse thereof. This not only prevents operation of the tripping toggle 107-109 but positively restrains the contacts in closed position.

This locking mechanism includes a cam member 209 secured to a shaft 211 rotatably supported in spaced brackets 213 which are suitably secured to and supported by the sides of the frame 16. Also secured to the shaft 211 is an arm 215 having its free end formed back on the body of the arm as at 217. A pivot pin 219 is supported in the arm 215 and the formed end 217 thereof and a linkage 220 including a short rod 221 disposed in the U-shaped end of the arm is pivotally connected to the pin 219. The short rod 221 is threaded and thereby adjustably secured in the end of a larger rod 223 having an axially disposed opening in its other end. One end of a rod 225 is inserted in the opening and secured to the rod 223 by means of a pin 227, the other end of the rod 225 extending through a guide opening in an insulating plate 229 secured to the bracket 143. A spring 231 compressed between the end of the rod 223 and the plate 229, biases the rod assemblage toward the left which movement is limited by an operating knob 233 secured to the outer end of the rod 225 and resting against the outer face of the plate 229.

The locking device is operated by manually grasping the knob 233 and drawing the linkage 220 outwardly. This rocks the arm 215, the shaft 211 and the cam member 209 in a clockwise direction as viewed in Fig. 1. At this movement of the cam 209 a projection 235 thereon engages the yoke 106 of the lever 105 and rocks the lever 105 slightly counterclockwise. This removes from the tripping toggle 107-109 the biasing force of the springs 85 transmitted through the contact arm 30, the main operating toggle 93-95, the lever 89, the link 103 and the lever 105, consequently any force applied to operate the tripping toggle 107-109 either as a result of operation of the trip device 133 in response to overload currents, or by operation of the handle 141 is ab-

sorbed by the cam 209 and tripping of the breaker is defeated.

In addition to preventing operation of the tripping toggle 107-109 the cam 209 when moved to its locking position beneath the yoke 106 acts also to prevent opening of the contact arm and contact. When the cam 209 is operated it locks the lever 105 against clockwise movement. Since the lever 105 is held against movement it follows that the lever 89 through the link 103 is held immovable. With the lever 89 held against movement and the force of the springs 85 and the springs 53 and 63 restraining the main operating toggle 93-95 in the over center position it can be seen that a substantially solid linkage is effective through the operation of the cam 209 to maintain the contacts closed.

When it is desired to restore the circuit breaker to its normal functions the knob 233 is released and the spring 231 shifts the linkage 220 toward the left rocking the cam 209 counterclockwise. As the cam frees the yoke 106 the spring 128 immediately sets the tripping toggle 107-109 overcenter to the position shown without tripping the breaker.

Figs. 3, 4 and 5 illustrate another embodiment of the invention. In the case of ordinary shocks below a predetermined force the tension of the springs 85, 53 and 63 is sufficient to hold the main operating toggle 93-95 overcenter above the center line 99-101 and thus prevent accidental opening of the breaker due to jars or shocks which might otherwise jar the toggle 93-95 overcenter in a direction to permit opening of the contacts.

A very heavy shock above the predetermined force might however cause the toggle 93-95 to break overcenter below the line 99-101 and cause interruption of the power supply at a vital moment even though the previously described locking mechanism is effective to prevent operation of the tripping toggle 107-109.

The purpose of the embodiment of the invention shown in Figs. 3, 4 and 5 is, therefore, to positively lock the main operating toggle 93-95 as well as the tripping toggle 107-109 against operation and thus positively lock the contacts in their closed circuit position. This embodiment of the invention is illustrated as applied to the previously described circuit breaker mechanism and corresponding parts thereof have been given the same reference characters.

It will be remembered that after the breaker has been tripped and moved to the open circuit position either in response to an overload current or manually, the contacts are reclosed by operation of the contact closing lever 145 (Figs. 1 and 3). In accordance with the embodiment shown in Figs. 3, 4 and 5 the contacts are adapted to be locked in the closed position by interposing a locking member in the return path of travel of the closing lever thus positively holding the toggle 93-95 overcenter in the position where it is effective to positively lock the contacts in closed position.

The locking member comprises a lever 237 (Fig. 3) pivotally supported on a stud 239 mounted in an upwardly extending portion 240 of the frame member 16. The lower portion 241 of the lever 237 is formed at an angle to the main body of the lever and is adapted, when operated, to engage a roller 243 rotatably mounted on a stud 245 projecting laterally from the closing lever 145. The lever 237 comprises a longer lever which in-

cludes the angular portion 241, and a shorter lever 247 disposed on the opposite side of the frame 16. The levers 237 and 247 are rigidly connected by a cross member 249.

The lower end of the lever 247 is rounded and is adapted to engage a curved extension 251 of the yoke 104 connecting the sides of the previously described link 103 for the purpose of preventing operation of the tripping toggle 107-109 as will be more fully brought out later.

In order to operate the locking lever 237 there is provided a pull rod assembly 253 which includes a rod 255 slidably and rotatably mounted in openings in an extension of the insulating plate 229 and in the base 11 of the breaker. The rod 255 extends to the left (Fig. 3) of the base 11 and has a collar 257 secured on the end thereof. A restoring spring 259 is compressed between the collar 257 and a washer 261 disposed against the base 11.

The pull rod 255 is operatively connected to the locking levers 237-247 by means of a member 263 which is movable longitudinally with the rod 255 but which permits rotation of the rod therein. The member 263 is disposed between the upper ends of the levers 237 and 247 and is provided with an open slot 265 in the lower part thereof which engages a pin 267 mounted in the upper ends of the levers 237 and 247.

The member 263 is mounted on a reduced portion of the rod 255 and a sleeve 269 is secured to the reduced portion between the base 11 and the member 263 to prevent movement of the member 263 axially on the rod but which at the same time permits rotation of the rod 255 relative to the member. The sleeve 269 also acts to limit the unlocking movement of the rod assembly. Washers 271 and 273 are provided to absorb the thrust wear between the sleeve 269 and the base 11 and the member 263. An operating knob 275 is secured to the outer end of the pull rod 255.

Assuming the breaker to be in an open position and that it is desired to close the contacts and lock them in closed position. The operator first closes the breaker by rotating the handle 141 in closing direction. This movement, as previously described, rotates the closing lever 145 in a clockwise direction through the agency of the crank arm 144 (Fig. 1), the link 151 and the roller 153. Clockwise rotation of the closing lever 145 engages the roller 155 with the toggle 83-85 and straightens this toggle thereby closing the contacts. While holding the closing handle in closed position the operator grasps the knob 275 and draws the rod 255 outwardly, i. e., toward the right (Fig. 3).

This movement of the pull rod due to the connection 265-267 rocks the levers 237 and 247 clockwise about their common pivot 239. At this movement the rounded lever end of the lever 247 engages the extension 251 of the yoke 104 and prevents operation of the tripping toggle 107-109 by preventing clockwise rotation of the lever 105. Thereafter the beveled end of the lever 237 moves into the path of the roller 243 thus holding the closing lever 145 in its operated position.

If the breaker is already closed and it is desired to lock it in closed position the only operation required is to draw the rod to locking position. In this condition of the breaker the closing lever occupies the position in which it is shown in Figs. 1 and 3, and clockwise movement of the lever 237 engages the angular portion 241 thereof with the roller 243 and rotates the clos-

ing lever clockwise to its closing position. Near the end of this movement the beveled end of the lever 237 assumes its position in the path of the roller thus retaining the closing lever in the operated position.

After the pull rod 255 has been drawn out to its locking position it is desirable to lock it against the unlocking influence of the spring 259. This is accomplished by rotating the pull rod 255 in a clockwise direction (Figs. 4 and 5) after it is moved to locking position. This movement engages a locking member 277 (Figs. 3 and 5), secured to the rod 255, with a notch 279 in a projection 281 of a fixed plate 283 mounted on a barrier 285 disposed between adjacent poles of the breaker. A member 287 integral with the member 277 engages the under side of the projection 281 to limit the unlocking rotation of the pull rod 255. The locking rotation of the rod is limited by engagement of the locking member 277 with the upper edge of the extension 281.

In order to unlock the pull rod 255 it is first pulled out slightly to disengage the member 277 from the notch 279 and then rotated counter-clockwise (Figs. 4 and 5). A pointer is provided on the knob 275 and an index plate 289 is secured to the insulating plate 229 to indicate the locked and unlocked positions of the rod 255.

After the rod 255 has been unlocked it may be released and the spring 259 will restore the rod and the levers 237 and 247 to their ineffective positions. As soon as the lever 237 clears the roller 243 the previously described spring 153 acts to rock the closing lever 145 counterclockwise to its normal position.

Under normal conditions the circuit breaker is trip free of the handle, that is, if the breaker should be closed against an overload it will immediately trip open even though the handle is held in the closed position. The circuit breaker may, however, be closed against an overload and locked in the closed position by proper manipulation of the locking device and the operating handle.

It will be remembered that when the circuit breaker is tripped open either manually or in response to an overload current the linkage including the lever 89, link 103, lever 105 and the tripping toggle 107-109 (Fig. 3) is automatically reset to its normal position. In order to close and lock the breaker against an overload the pull rod 255 is first drawn outwardly rocking the levers 237-247 clockwise far enough to engage the lever 247 (Fig. 3) with the projection 251 of the yoke 104 thus locking the tripping toggle against operation to trip the breaker when the contacts are closed. The operating handle 141 is then rotated in closing direction, operating the closing lever 145 to close the contacts in the previously described manner. The pull rod 255 is now drawn outwardly to full locking position. This completes the clockwise movement of the levers 237-247 and engages the lower portion 241 thereof with the roller 243 to positively lock the contacts in their closed position.

Having described several embodiment of the invention in accordance with the patent statutes, it is to be understood that various changes and modifications may be made therein without departing from some of the essential features of the invention. It is, therefore, desired that the language of the appended claims be given as reasonably broad interpretation as the prior art permits.

We claim as our invention:

1. A circuit breaker comprising a contact member movable to an open position and to a closed position, a toggle operable to cause an opening movement of said contact member, means operable solely to move the contact member to closed position, and a pivoted lever having a part engageable with a part movable with said toggle and a part engageable with the closing means for moving said closing means to close position to prevent opening movement of the contact member.

2. A circuit breaker comprising a contact member movable to an open position and to a closed position, a toggle operable to cause an opening movement of said contact member, a closing lever operable to move the contact member to closed position, a pivoted member engageable with a part movable with the toggle to prevent operation of said toggle, said pivoted member having a part engageable with the closing lever to move said lever to closed position and to hold said closing lever in closed position, and manually operable means for operating the pivoted member.

3. A circuit breaker comprising a contact member movable to an open and to a closed position, a linkage operable to initiate an opening movement of the contact member, means engageable with a part of said linkage to prevent initiation of an opening movement of the contact member, closing means engageable with another part of said linkage to move the contact member to closed position, and means operable to hold said closing means in engagement with said linkage.

4. A circuit breaker including separable contacts, operating mechanism for said contacts including a manual operating member operable to cause opening of the contacts, a linkage for holding the contacts in closed position independently of said manual operating member, said linkage including a toggle operable to cause opening of the contacts, said manual member also being operable to close the contacts, a trip device operable in response to predetermined abnormal circuit conditions for operating the toggle to cause opening of the contacts irrespective of the position of the manual operating member, and manually operable means engageable with a part of said linkage for positively holding the contacts in closed position and also for preventing operation of said toggle by said trip device.

5. A circuit breaker comprising separable contacts, operating mechanism for said contacts, said operating mechanism including a manual operating handle movable in one direction to cause opening of said contacts and in another direction to close said contacts, a linkage for holding the contacts in closed position independently of said handle, said linkage including a toggle operable by said handle to cause opening of said contacts, current responsive means for operating said toggle to open the contacts

irrespective of the position of the handle, and locking means settable to a locking position in which it prevents operation of the toggle by said handle and also by said current responsive means and also positively locks the contacts closed.

6. A circuit breaker comprising a contact member movable to an open position and to a closed position, a toggle operable to initiate a movement of the contact member to open position, closing means comprising a lever operable solely to move the contact member to closed position, manually operable means movable to an intermediate position wherein a portion thereof engages a part at all times movable with said toggle to prevent initiation of an opening movement of the contact member, said manually operable means being movable to a locking position wherein said portion thereof engages a part movable with the toggle to prevent initiation of an opening movement of the contact member and another portion thereof engages said closing lever to positively hold said contact member in closed position.

7. A circuit breaker having a movable switch member biased to open circuit position, operating mechanism therefor comprising an operating toggle connected to said switch member, a linkage pivotally connected to one end of said toggle normally restraining said one end of said toggle in operative position, a pivoted operating lever operable solely to actuate said toggle to move said switch member to closed position, a trip device operable to cause said linkage to release said end of said toggle and thereby cause movement of the switch member to open circuit position, said linkage and said one end of said toggle being automatically reset to normal position following tripping of the breaker, and manual means for preventing operation of said linkage and release of said one end of said operating toggle when the switch member is being moved to closed position.

8. A circuit breaker having a movable switch member biased to open circuit position, operating mechanism therefor comprising an operating toggle connected to said switch member, a linkage pivotally connected to one end of said toggle normally holding said one end of said toggle in operative position, an operating lever operable solely to actuate said toggle to move said switch member to closed position, a trip device operable to cause said linkage to release said end of said toggle and cause movement of the switch member to open position, said linkage and said one end of said toggle being automatically reset to normal position following tripping of the breaker, and manually operable means engageable with said linkage to hold said one end of said toggle in operative position while the breaker is being closed.
